DESIGN FOR A TEXTILE FABRIC

Samuel T. Palay, New York, N. Y.

Application March 17, 1939, Serial No. 83,648

Term of patent 3½ years

To all whom it may concern:

Be it known that I, Samuel T. Palay, a citizen of the United States, and a resident of the city of New York, in the county of New York and State of New York, have invented a new, original, and ornamental Design for a Textile Fabric, of which the following is a specification, reference being had to the accompanying drawing, constituting a part thereof.

The figure is a plan view of a piece of the fabric showing my new design.

I claim:

The ornamental design for a textile fabric, substantially as shown.

SAMUEL T. PALAY.
